Primary Examiner — Jack Reickel*Assistant Examiner* — Russell Carnell Smith, Jr.*(74) Attorney, Agent, or Firm* — Vani Moodley, Esq.(57) **CLAIM**

The ornamental design for a mount for a video bar, as shown and described.

DESCRIPTION

FIG. 1 is a first perspective view of the mount for a video bar, showing our new design.

FIG. 2 is a second perspective view of the mount for the video bar.

FIG. 3 is a front view of the mount for the video bar.

FIG. 4 is a rear view of the mount for the video bar.

FIG. 5 is a left view of the mount for the video bar.

FIG. 6 is a right view of the mount for the video bar.

FIG. 7 is a top view of the mount for the video bar; and,

FIG. 8 is a bottom view of the mount for the video bar.

Any broken lines in the drawings depict portions of the mount for the video bar that form no part of the claimed design.

1 Claim, 7 Drawing Sheets(56)
